INVENTOR

BY Harry Schroeder

ATTORNEY

UNITED STATES PATENT OFFICE.

JACOB HENRY BECKMAN, OF OAKLAND, CALIFORNIA.

AMMONIA CONDENSER.

Application filed January 4, 1927. Serial No. 159,011.

My invention relates to improvements in ammonia condensers, and it consists in the combinations, constructions, and arrangements, hereinafter described and claimed.

5 An object of my invention is to provide an ammonia condenser which causes the gases to flow from a common header through a plurality of pipes connected with the header, and which has means for cooling the pipes with 10 water, the water being directed over each pipe by baffles whereby the pipes are effectually cooled.

A further object of my invention is to provide a device of the type described in which 15 air is passed over the pipes and through the water for cooling the pipes and the water.

A further object of my invention is to provide a device of the type described in which the pipes are provided with stops for causing 20 the liquid ammonia to flow in one direction through the pipes.

Other objects and advantages will appear in the following specifications and the novel features of the invention will be particularly 25 pointed out in the appended claims.

My invention is illustrated in the accompanying drawing forming a part of this application in which

30 Figure 1 is a side elevation of the device, Figure 2 is a section along the line 2—2 of Figure 1,

Figure 3 is a side elevation of the device with the casing removed,

35 Figure 4 is a section along the line 4—4 of Figure 5,

Figure 5 is an enlarged detailed view of a portion of the device,

Figure 6 is a section through one of the pipes, and

40 Figure 7 is a view of a partition used in the device.

In carrying out my invention, I provide a catch basin 1 to which an outlet pipe 2 is connected, the pipe 2 in turn being connected to a pump 3. A pipe 4 leads from the pump 3 to a plurality of outlet nozzles 5. The nozzles 5 are disposed above a condenser now to be described.

The condenser comprises two vertical headers 6 and 7, which communicate with horizontal headers 8 and 9 respectively. A plurality of pipes 10 connect the headers 6 and 7 together. An inlet pipe 11 communicates with the header 8 while an outlet pipe 12 communicates with the header 9. It will be noted from Figure 3 that the header 8 is disposed above

the header 9 and that a pipe 13 connects the headers together for a purpose hereinafter described.

A casing 14 encloses the condenser and is formed with a plurality of partitions 15, side-wall section 16 and top section 17. The partitions 15 are formed in two parts, each part having semi-circular recesses 18 therein for receiving the pipes 10 and inclined grooves 19 65 therein for receiving baffles 20, as clearly shown in Figure 7.

The partitions 15 carry lugs 21 to which the side sections 16 and the top sections 17 are bolted. The headers 6 and 7 also carry lugs 70 22 for supporting certain of the sections 16 and 17.

It will be noted from Figure 2 that the casing 14 is open at its lower end and has an air pipe 23 communicating with the top thereof. 75 This pipe connects with an air pump 24 which sucks the air up through the interior of the casing 14, the air passing over pipes 10 and the baffles 20 thus effectually cooling the water and the pipes.

In Figure 6 I show the pipe 10 as being provided with a stop 24, disposed adjacent to the header 6. This stop prevents the liquid ammonia from flowing into the header 6 and causes it to flow into the header 7.

80 From the foregoing description of the various parts of the device, the operation thereof may be readily understood. The ammonia in a gaseous state flows from the pipe 11 into the headers 8 and 6 and then through 90 the pipes 10. The ammonia is changed into a liquid state as it passes through the pipes 10 and is then conveyed to the headers 7 and 9 and out through the pipe 12. As heretofore described the stops 24 in the pipes 10 cause 95 the ammonia liquid to flow into the header 7 instead of into the header 6.

In case any of the ammonia condenses in the header 6 and falls into the header 8, this liquid ammonia may be conveyed to the header 100 9 by means of the pipe 13. A valve 25 controls the flow of liquid in the pipe 13.

It will also be noted in Figure 3 that I provide oil pipes 26 and 27 communicating with the headers 8 and 9 respectively. These 105 pipes are for the purpose of draining off any oil which might collect in the bottom of the headers 8 and 9. The partitions 15 confine the water delivered from each nozzle 5 to a certain area of the pipes 10. The baffles 20 110 cause this water to flow over the pipes 10 in a film which hugs the pipes. As heretofore

stated the air is sucked through the casing 14 by means of the pump 24, and cools the water and the pipes.

The mixture of the air with the ammonia gases produces a certain amount of non-condensable gas which has a tendency to build up sufficient pressure in the piping system of the condenser to prevent the flow of the ammonia gases therethru. In order to maintain the ammonia flow thru the pipe the non-condensable gases, that are lighter than the ammonia gas, rise in the header 7 into chamber 28, which is so designed that a plurality of headers may be connected thereto. The non-condensable gases then rise into the container 29 and may be passed off thru a valve 30. There may be some non-condensable gas produced in the ammonia which is heavier than the ammonia gas, or the condensate, and these gases will flow with the condensate and may be tapped after passing thru the header 9. It will be recognized that with the aid of the container 29 and valve 30 and the header 9, the piping system of the condenser is always kept clear of any non-condensable gas that tends to clog the passage of the ammonia gases therethru.

I claim:

1. A device of the type described, comprising a plurality of pipes, means for conveying

water to said pipes, baffles for causing the water to flow in a film over each pipe and to hug the pipes, and means for drawing air past said pipes and through the water.

2. A device of the type described, comprising a horizontal header, a second header mounted at a lower level than the first header, condenser means connecting said headers together, and a pipe for connecting said headers together for conveying any liquid from the higher header to the lower header. 35

3. A device of the type described, comprising a horizontal header, a second header mounted at a lower level than the first header, condenser means connecting said headers together, and a pipe connecting said headers together for conveying any liquid from the higher header to the lower header, and an oil conveying pipe communicating with the bottom of said headers. 45

4. In a device of the type described, a condenser, a sectional casing disposed around said condenser, said casing providing an inlet and an outlet for air, and comprising partitions, means carried by said partitions for removably supporting baffle plates, baffle plates secured to said partitions, and wall and top sections secured to said partitions. 50

In testimony whereof I affix my signature.

JACOB HENRY BECKMAN.
